UNITED STATES PATENT OFFICE.

CHRISTOPHER J. THEUERNER, OF NEWARK, NEW JERSEY.

DESIGN FOR A FINGER-RING.

SPECIFICATION forming part of Design No. 14,351, dated October 16, 1883.

Application filed July 16, 1883. Term of patent 7 years.

To all whom it may concern:

Be it known that I, CHRISTOPHER J. THEUERNER, of Newark, in the county of Essex and State of New Jersey, have invented and produced a new and original Design for Finger-Rings, of which the following is a full, clear, and exact description.

My design relates more particularly to that class of finger-rings having a gem or stone set in a box or frame fixed to the shank of the ring, but is applicable to rings having a solid metal or other projecting head piece or plate.

Figure 1 is a perspective view of a ring with an intaglio set therein, also representative of my design. Fig. 2 is an edge view of the ring.

There is no novelty in the configuration of the shanks or gem-boxes of the ring, but in an alphabetical symbol or symbols placed at, across, or near the junction of the ring-shank with the head-piece or gem-box.

In the drawings, A represents the ring-shank, and B the head or gem-box. In this box any style of gem or stone, C, may be set, as shown. The especial configuration of the stone or gem C forms no part of my design. A letter or alphabetical character is arranged in relief on the ring-shank at the point of junction at both sides of the gem-box. It is evident that any desired style or size of alphabetical character may be formed on the ring at the points indicated.

What I claim is—

The design for a finger-ring, having alphabetical characters on each side spanning the junction of the gem-box and ring-shank, as shown and described.

CHRISTOPHER J. THEUERNER.
